UNITED STATES PATENT OFFICE

2,451,093

KEY CASE

Bernard H. Kaminer, Brooklyn, N. Y.

Application March 25, 1946, Serial No. 656,967

2 Claims. (Cl. 70—456)

1

This invention relates to a key case having a pivotally mounted cover in which keys are pivotally mounted and whereby the keys are projected from the receptacle when the cover is swung into open position.

An object of this invention is to form the receptacle and key carrying cover so that when the keys are projected therefrom the receptacle may assume an angular position to one of the keys when the key is in the lock.

Another object of this invention is to provide hinge means for pivotally mounting the cover on the receptacle and to provide resiliently actuated catch means opposite the hinge means and whereby the cover may be automatically locked on the receptacle.

Another object of this invention is to slot the cover along one of its upright sides and along more than half the length of its top wall so as to permit a key to swing outwardly from the receptacle when the cover is opened and to permit the cover to be locked to the receptacle while the key is projecting in operating position outside the receptacle.

With the above and other objects in view, the invention will be hereinafter more particularly described, and the combination and arrangement of parts will be shown in the accompanying drawings and pointed out in the claims which form part of this specification.

Reference will now be had to the drawings, wherein like numerals of reference designate corresponding parts throughout the several views, in which:

Figure 1 is a front elevation of the key case in closed position.

Figure 2 is a front elevation of the key case with the cover in open position.

Figure 3 is a front elevation of the key case with the cover swung open into right-angular relation with the receptacle.

Figure 4 is a cross-sectional view of the key case shown in Figures 1 to 3, inclusive, the section being taken as on line 4—4 in Figure 1.

Figure 5 is a view of a fragmentary portion of the key case showing the catch means in operating position.

Figure 6 is a front elevation of the catch means.

Figure 7 is a view of a fragmentary portion of the key case showing the hinge means in operating position.

Figure 8 is an end view of a modified key case showing the cover centrally slotted along two adjacent walls.

2

Figure 9 is a top plan view of the key case shown in Figure 8.

Figure 10 is a side elevation of the key case shown in Figures 8 and 9, the cover being partly broken away.

In the illustrated embodiment of the invention, the numeral 10 indicates a key case comprising a receptacle 11 preferably of rectangular cross-section. The receptacle 11 has an opening 12 at

10 its upper end.

Keys 13 are pivotally mounted in face-to-face relation on a pivot 14 in a hollow cover 15. The cover 15 is pivotally mounted on the receptacle 11 on a hinge 16 and may be swung into open or 15 closed position with relation to the receptacle 11. The keys may be withdrawn from the receptacle 11 through the opening 12 by swinging the cover 15 on the hinge 16. A coil spring 17 is mounted on the pintle of the hinge 16 and is arranged to 20 cause the cover to automatically swing into open position.

The receptacle 11 has catch means 18 secured to the wall 19 opposite the hinge 16. The catch means 18 comprises a leaf spring 20, the lower end 25 of which is suitably fixed to the wall 19, such as by rivet 21. The upper end of the leaf spring 20 has an angularly bent portion 22 facing outwardly of the receptacle. The free end of the leaf spring 20 is beveled. The cover 15 has a lip 24 positioned 30 horizontally at the line of contact 25 between the cover and the receptacle.

The leaf spring 20 has a push button 26 fixed thereto in any suitable manner, such as by riveting its inner end to the leaf spring 20. The 35 wall 19 has an aperture 27 through which the body of the push button 26 passes outwardly of the receptacle 11. The push button has a rounded outer end against which the user applies pressure to force the leaf spring 20 inwardly to permit the cover 15 to swing into open position.

As best shown in Figure 4, the pivot 14 has a cylindrical body 30 on which the keys are pivotally mounted. The body 30 passes through an aperture 31 in the cover 15. The body 30 has 45 a threaded end portion 32 of smaller diameter than the cylindrical body, the pivot 14 being threadably secured in a threaded aperture 33 in the cover 15, in alignment with the aperture 31.

The apertures 31 and 33 serve as bearings for 50 the pivot 14. It is to be noted that the pivot 14 is positioned parallel to the line of contact 25 between the cover and the receptacle.

Figures 8 to 10, inclusive, show a modified key case 35, comprising a receptacle or hollow body 55 11 and a hollow cover 36, pivotally mounted on

the receptacle on a hinge 16. The cover 36 is similar to the cover 15, but in addition is slotted centrally of the key case at 37, along the entire length of one of its upright sides.

The slot 37 extends from the line of contact 25 between the cover and the receptacle and terminates in the upper wall 38 of the cover 36 at a point beyond the pivot 14 to permit the key 13 to project in operating position outside the receptacle and in right angular relation with the receptacle.

In the position shown in Figure 10 the key 13 is indicated as inserted into the ignition lock 39 of an automobile, the body of the key case hanging vertically from the pivot 14 in the head of the key 13. The receptacle is in operating position, held in depending relation from the key 13.

It is to be noted that the slot 37 is centrally positioned in relation to the key case and that the slot is preferably made wider than one of the keys to permit a selected key in the plurality of keys mounted in the key case to be aligned with relation to the slot so as to permit the key to be projected outwardly from the slot while confined between the walls of the slot.

In accordance with the patent statutes I have described and illustrated the preferred embodiment of my invention, but it will be understood that various changes and modifications can be made therein without departing from the spirit of the invention as defined by the appended claims.

I claim:

1. In a pocket size key case, a receptacle of rectangular cross-section and comprising two narrow end walls and two wide side walls respectively lying in parallel planes, said walls being solid and non-separable and having an opening at its upper end, a cover having bearing means centrally thereof and being hingedly mounted on said receptacle at said open end, said hinge being mounted on one of said end walls to cause said cover to swing clear of said receptacle, said cover being of a size to close said opening, catch means secured to said case on the side opposite said hinge to automatically lock said cover on said receptacle, key-carrying means detachably mounted in said bearing means, said key-carrying means being positioned transversely of said cover to permit said keys to swing outwardly from said receptacle when said cover is swung into open position, said keys being movable into con-

cealed relation within said receptacle when said cover is moved into closing position, said cover being centrally slotted on two adjacent sides to permit the body of one of said keys to project in operating position outside said receptacle with the head of said key projecting outside the boundaries of said cover while said receptacle is held in depending relation from said key.

2. In a pocket size key case, a receptacle of rectangular cross-section and comprising two narrow end walls and two side walls lying in parallel planes, said walls being integral and non-separable, said receptacle having an opening at its upper end, a cover of rectangular cross-section having bearing means centrally thereof, said cover being hingedly mounted on said receptacle at said open end, said hinge being mounted on one of said end walls to cause said cover to swing clear of said receptacle, said cover being of a size to close said opening, catch means secured to said case on the side opposite said hinge to automatically lock said cover on said receptacle, threaded key-carrying means detachably mounted in said bearing means, said key-carrying means being positioned to permit said keys to swing outwardly from said receptacle while confined between said parallel sides, said keys being movable into concealed and enclosed relation within said receptacle when said cover is moved into closing position, said cover being centrally slotted to permit the body of one of said keys to project in operating position outside said receptacle with a portion of the head of said key projecting outside the boundaries of said cover while said receptacle is held in depending relation from said key and while said key is confined between the walls of said slot.

BERNARD H. KAMINER.
